(57) CLAIM

The ornamental design for a garden trunk, as shown and described.

DESCRIPTION

FIG. 1 is a perspective view of a garden trunk showing my new design.

FIG. 2 is a front view thereof;

FIG. 3 is a rear view thereof;

FIG. 4 is a side view thereof;

FIG. 5 is an opposite side view thereof; and,

FIG. 6 is a top view thereof.

The features presented in broken lines represent unclaimed portions of the garden trunk and form no part of the claimed design.

1 Claim, 4 Drawing Sheets
